UNITED STATES PATENT OFFICE.

PRESTON ELWOOD GILLING, OF SUMTER, SOUTH CAROLINA, ASSIGNOR TO SPLITDORF ELECTRICAL COMPANY, OF NEWARK, NEW JERSEY, A CORPORATION OF NEW JERSEY.

DESIGN FOR A BICYCLE-LAMP.

51,138.

Specification for Design.

Patented Aug. 14, 1917.

Application filed February 19, 1917. Serial No. 149,685. Term of patent 3½ years.

To all whom it may concern:

Be it known that I, PRESTON ELWOOD GILLING, a citizen of the United States, residing at Sumter, in the county of Sumter and State of South Carolina, have invented a new, original, and ornamental Design for Bicycle-Lamps, of which the following is a specification, reference being had to the accompanying drawing, forming part thereof.

In the drawing,—

Figure 1 is a perspective view from the front of the lamp;

Fig. 2 is a perspective view from the rear of the lamp.

I claim:

The ornamental design for a bicycle lamp, as shown.

PRESTON ELWOOD GILLING.
